DESIGN FOR A TEXTILE FABRIC

John H. Huelat, New York, N. Y.

Application April 3, 1937, Serial No. 68,540

Term of patent 3½ years

To all whom it may concern:

Be it known that I, John H. Huelat, a citizen of the United States of America, residing in Manhattan, county of New York, and State of New York, have invented a new, original, and ornamental Design for a Textile Fabric, of which the following is a specification, reference being had to the accompanying drawing, forming part thereof, wherein,

The figure is a front view of a piece of textile fabric showing my new design.

The leaves are depressed below the level of the background, as shown.

I claim:

The ornamental design for a textile fabric, substantially as shown and described.

JOHN H. HUELAT.
